UNITED STATES PATENT OFFICE.

CHARLES W. MORGAN, OF CHICAGO, ILLINOIS, ASSIGNOR OF ONE-HALF TO ANDREW C. LYEN, OF CHICAGO, ILLINOIS.

VISE.

Application filed September 27, 1922. Serial No. 590,933.

To all whom it may concern:

Be it known that I, CHARLES W. MORGAN, a citizen of the United States, and a resident of the city of Chicago, in the county of 5 Cook and State of Illinois, have invented a new and useful Vise, of which the following is a full, clear, and exact description.

My invention relates to improvements in vises or holding appliances used in bench 10 testing of small machines such as automobile magnetos, generators or starters; and the object of my improvement is to provide a vise with adjustable jaws to grip machines of various dimensions and only at points 15 that can safely withstand pressure from the jaws; or are particularly accessible.

I attain the object of my invention by the use of three adjustable clamping members, two of which are located on one side of a 20 machine to be secured in the vise and the third of which is located on the other side.

I incorporated three adjustable, clamping members in a vise for the first time, in what 25 I choose to term the original form described in this specification; and later, I simplified the structure of my vise in what I term the improved form described in a supplementary specification.

In the drawings forming a part of this 30 specification, like characters of reference indicate corresponding parts in all views. Fig. 1., shows the original form of my vise completely assembled; Fig. 2., a side and rear elevation of the front adjustable arm and its locking member; Fig. 3., a plan view of the pressure screw block; Fig. 4., a rear L-member; Fig. 5., a plan view of the carriage lock; Fig. 6., diagrammatic plan views of the vise holding a long generator of small diameter and also holding 35 a short generator of large diameter.

I will now describe my vise shown in Fig. 1. 1 is the carriage of the vise supported on parallel guiding members or rods 2, 2. 45 These members 2, 2 permit a forward or backward adjustment of carriage 1. The carriage may be locked rigidly to the guiding members or rods by means of the L-shaped lock 3 and the set screw 4. This lock 3 is shown in greater detail in Fig. 5. Referring to Fig. 5., a screw 5 is used to hold the lock in place when pushing the carriage forward on the parallel rods. In carriage 1, there is a trough 6 running parallel to the rods 2, 2. In this trough and

lying below the surface of the carriage, there is a rod 7 rigidly mounted at each end in the casting of the carriage. A hole 8 in the vertical wall of the trough, forms the support for one end of the rod 7 while a hole in an extension 9 of the carriage forms the support for the other end of 7. Pivotally mounted on this rod 7, slides an arm 10 and arm lock 11. See also Fig. 2. The set screw 12 in the tapped end of lock 11, when tightened, cant the arm 10 on the rod 7 so as to make it seize. This assists the normal tendency of the arm to cant and seize when it receives pressure from a device being held in the vise. Pressure from such a device is indicated by an arrow in Fig. 2. Referring to Fig. 1., and Fig. 3., surrounding both 10 and 11 there is an adjustable block 13. This block is provided with sufficient clearance so that it may be 70 slid up or down on 10 and 11. The push screw 14 mounted in 13 exerts pressure against the device being held in the vise. Two movable L-shaped members 15, 15 Fig. 1., and Fig. 4., form the rear clamping 80 members or rear jaw of the vise. A rod 16 perpendicular to the rods 2, 2 forms the guide for the members 15, 15. The horizontal parts 17, 17 on the L-members 15, 15 press upward on the under side of the carriage. 85

Having described the essential parts composing my original form of vise, I will now describe its use. The magneto, generator or starter to be secured in my vise is placed 90 on the carriage 1, Fig. 1., in proper alignment with the pulley of the motor that is to drive it and the rear L-members are adjusted to suit its particular dimensions. Then the push screw arm 10 with its lock 95 11 and surrounding block 13 are pushed up against the magneto so that the pressure screw 14 presses at a desirable point. Set screw 12 is then tightened thus locking 10 rigidly on rod 7 and final pressure is secured 100 by turning 14 to the limit of strain desired. When removing work from the vise, the pressure screw and lock are released, the whole unit brought back and rotated to the right or left below the surface of the carriage thus leaving the space clear in front 105 to remove the work.

In Fig. 6., (a) and (b), I show plan view diagrams of my vise holding generators of different diameters. On generator 27 there 110

happens to be rigid bracket 29 attached to it at the rear side and a frail box 30 containing delicate mechanisms attached to it on the front side. I represent the two members 15, 15 by black arrows and the pressure screw 14 by a third arrow. These arrows are numbered to correspond with the objects which they represent. The broken line AB represents the center line of a belt or chain for driving the machine under test. In both figures the carriage is shown at the same distance from AB. Now by closely studying both conditions (a) and (b) it will be apparent that to accommodate both generators 27 and 28, the jaws of the vise must be adjustable as described. If the members 15, 15 were not adjustable but fixed in the positions indicated in (a) it is plainly apparent they could not accommodate generator 28 in (b). And too, if the rear jaw of my vise were composed of a single rigid member extending transversely from one side of the vise to the other, the peculiar shape of the lug 29 on 27 would interfere. Furthermore, if 27 had no lug 29, the width of the solid rear jaw would cause it to interfere with the accessibility to the brush rigging at the rear of generator 28. As to the advantages of adjusting front jaw 14, it is evident that were 14 fixed centrally while it would accommodate 27, it would press close to or against the delicate brush rigging on 28 and were it located to accommodate 28 satisfactorily, it would then be obliged to press against the delicate mechanism 30 on 27.

I am not aware that prior to my invention any vise has been made with three adjustable clamping members and therefore I claim this feature broadly.

I claim:

1. In a vise or holding appliance, the combination of three laterally adjustable clamping members to grip a device secured in it, two of said laterally adjustable clamping members being located on one side of the device and the third laterally adjustable clamping members on the opposite side.

2. In a vise or holding appliance, the combination comprising a carriage mounted on parallel guides; means of locking the carriage to the guides at any desired point; a rear jaw vertical to the upper face of the carriage and of adjustable width and position; a front jaw arranged to form an open-

ing of variable width between it and the rear jaw and arranged to press against the work secured in the vise at any desired point.

3. In a vise or holding appliance for bench testing of automobile magnetos, generators or starters, the combination comprising a carriage to receive the work; parallel guides or rods supporting the carriage; a lock to secure the carriage to the rods at any desired point; two L-shaped members forming the rear jaw of the vise each vertical to the carriage top and adjustable in a direction transverse to the parallel guides; a front jaw composed of a pressure screw mounted in a block, an arm and arm-lock adjacent thereto, the block being movable along the arm and lock; a rod acting as a pivotal support for the arm and arm-lock, the rod being rigidly fixed in portions of the casting of the carriage and lying in a trough in the carriage, the length of the rod and its position permitting movement of the arm and arm-lock toward or away from the two members forming the rear jaw.

4. In a vise indicated in Fig. 1, the carriage 1 to receive the work; the parallel rods 2, 2 mounted in the frames 2', 2', the said rods 2, 2 providing support for the carriage 1 and permitting a means of adjusting the position of the carriage; the lock 3 to secure the carriage 1 to the rods 2, 2 at any desired point; the members 15, 15 forming the rear jaw of the vise; the rod 16 to support members 15, 15, the said rod being supported at its ends in lugs forming a part of the carriage 1; the arm 10; the arm-lock 11 with set screw 12; the block 13; the screw 14, the said members 10, 11, 12, 13 and 14 composing in combination the front jaw of the vise; the rod 7 supported in portions of the carriage, to serve as a pivotal support for the arm 10 and arm-lock 11; all substantially as shown for the purpose specified.

5. In a vise or holding appliance, a rear jaw adjustable in width and position, and a front jaw having a pressure element adjustable transversely, longitudinally and vertically.

CHARLES W. MORGAN.
